UNITED STATES PATENT OFFICE.

JOHN L. POPE, OF CLEVELAND, OHIO.

DESIGN FOR A CARRIAGE-STEP.

SPECIFICATION forming part of Design No. 13,429, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for Carriage-Steps, of which the following is a specification, reference being had to the accompanying photographic illustration, forming part thereof.

My invention relates to a new design for carriage-steps; and it consists in forming in relief on the top or upper surface thereof a series of round and triangular figures and a central square-like figure; and it also consists in the shown foliation formed within the various figures.

In the accompanying photograph, *a a a a* are four round, and *b b b b* four triangular, figures, formed of raised or ribbed work; the former occupying positions at about the middle of each of the sides of the step and the latter placed at the corners thereof. Situated at about the center of the plate, and made up of ribs slightly curved, is a square-like figure, *c*.

Within each of the figures *a b c* may be formed, by open-work, the various designs shown. Inside of all the rings and triangles I have shown the plate cast with openings in the trefoiled form, the outer extremities of those within the rings being round, while the like parts of those within the triangular figures are pointed. Within the square-like figure *c* will be observed the outline of a quarterfoil with pointed extremities.

What I claim as my new design is—

1. A carriage-step having the round, triangular, and square figures of raised work, disposed in about the manner shown. 35

2. A carriage-step having the figures *a b c* and foliated open-work within them, substantially as shown. 40

In testimony whereof I have hereunto set my hand this 31st day of May, 1882.

JOHN L. POPE.

In presence of—

A. A. POPE,
C. M. COPP.
